DOUBLE GRIPPER CYLINDER

Louis Bischoff, Rupert Loeffler, Jr., and Edward T. Jaeger, New York, N. Y., assignors to Oneida Paper Products, Inc., New York, N. Y., a corporation of New York

Application April 20, 1938, Serial No. 203,030

1 Claim. (Cl. 93—8)

Our invention relates to a drum for holding creased bag bottoms during the bottom forming operation in bag making, and more specifically relates to a drum having double gripper mechanisms whereby, upon a bag bottom being creased into a slot in the drum of our apparatus, gripper arms move to hold such folded bag bottoms so that the creased bottoms can be properly folded in the formation of the bag bottom.

Heretofore in the formation of bag bottoms, it has been customary to use a creaser blade to stuff a portion of the bag bottom into a groove which may be, for example, rubber lined. There is a certain retention for the stuffed-in paper, but such mechanisms have been found to be lacking in the desired certainty of action which is necessary in the high speed and entirely automatic machine operations which are attendant upon the present day formation of bags. Thus, it has been found that, oftentimes, the creased or stuffed-in paper forced into the groove in the drum would have a tendency to escape from the groove, which, of course, would throw off completely the bottom forming operation and result in rejects.

We have conceived and developed a novel apparatus for surely and certainly maintaining the necessary creased portions of the bag bottom in proper position during the formation of the bag bottom. Thus, we have provided a drum with two sets of grooves. In the grooves, mechanisms are positioned which receive the bag bottom portions stuffed therein by creaser blades and proceed to firmly grip these creased portions to properly position and hold the creased portions during the bottom forming operation. Thus, as the folded paper passes over the drum and the creaser blades crease the proper portions of the paper into the grooves in the drum, synchronized gripper arms located in the grooves move so as to press firmly the creased-in paper and maintain it in that position until supplemental mechanisms have acted to fold over the ends of the creased paper to form the bag bottom. Thereupon the creaser arms move so as to release the creased-in paper and permit the bag to move on.

It is an object of our invention to provide a novel bag bottom gripper cylinder.

It is a further object of our invention to provide a novel cylinder having sets of multiple grooves wherein the creased portions of the bag bottom are firmly held during the bottom forming operation.

It is a further object of our invention to provide a double gripper cylinder wherein are located

gripper mechanisms which synchronously operate to hold the creased portion of the bag bottom during the bottom forming operation.

It is a further object of our invention to provide a drum which moves about a stationary cam so that in timed operation, gripper arms located within the gripper slots of the drum act to press and hold firmly creased paper sections.

Other objects will be apparent upon the description of the apparatus which will be set forth together with the following drawings:

In Figure 1 is shown an end view of the double gripper mechanism of our invention in combination with the creaser.

Figure 2 is a cross-section and partial elevation taken along the line 2—2 of Figure 1 looking in the direction of the arrows.

Figure 3 is a view taken along the line 3—3 of Figure 2 showing the double gripper apparatus of our invention in a modified position with the adjustment to form a wider bottom bag.

Figure 4 is a detail section taken along the line 4—4 of Figure 1.

Figure 5 is a section along the line 5—5 of Figure 1.

Figure 6 shows the bag in the course of the bottom creasing operation for which this apparatus is devised.

Figure 7 shows the completed bag and folded bag bottom.

Referring now more specifically to the drawings, we have shown in Figure 1 the folded paper 1 which travels along in the direction indicated by the arrow. The paper has been previously folded to tubular form. The forward end of the folded paper has been spread by suitable spreading mechanism into a diamond shape at its advancing end. As the advancing folded paper passes between the suitably mounted creaser blades 10 and the double gripper cylinder 11, the creaser blades 10 force the paper 1 into the grooves 12 and 13. As the drum moves and the creaser blades 10 are withdrawn from the grooves, the gripper arms 15 and 16 move against the creased paper to hold it in its proper position in the grooves. The gripper arms 15 and 16 move about the fixed pivots 17 and 18. The structure and power source of the gripper arm 16 will be specifically described since the multiplicity of gripper arms are actuated in a similar manner. Thus the gripper arm 16 is pivoted about the shaft 18. The movement of the gripper arm 16 is governed by the roller 20 mounted on the arm 21 by means of the pin 22. The roller 20 rides upon the cam surface 25 which has a high sur-

face 26 and a low surface 27. The roller is maintained against the cam by means of the spring 30 secured to a rigid member 31 on the frame and to the end of the arm 21 at the point 32. The arm 21 terminates in extension 33 so that the arm can be manipulated manually to open the gripper arm 16 if desired. Thus, in essence, the apparatus is operated by suitably timed cam action to cause the gripper arms to hold the crease in the paper which is to form the bag bottoms, as they are carried on the drum in a predetermined path.

The construction of the apparatus will now be set forth. The drum 50 has openings 51 with suitable surfaces 53 and 54 in which are set blocks 36 and 36'. The blocks are secured to the drum 50 by means of bolts 38 which are set in tapped holes 55 in the drum 50. In this block 36 is a groove 13 in which is set the gripper arm 16. The gripper arm, as shown in Figure 4, comprises a gripper surface 60 terminating in an extension 61. This extending surface of the gripper arm is engaged between the split members 62 and 63 of the arm 21. A bolt 64 tightens these split members together so that the arm 21 is rigidly fixed with respect to this integral shaft extension of the gripper arm 16. Adjacent to the grippers 16 and coacting therewith are the grippers 15 which are located in the block 35 mounted on the spoke 70 which terminates in a hub 71 rotating with the drum 50 about the shaft 41.

As shown in Figure 3, in order to secure varying bottom widths, as is necessary in different bags, adjustment is made possible between the block 35 and the block 36, to provide proper spacing therebetween, by moving the spoke 70 away from the block 36. This is made possible by means of the slotted members 75 and bolts 76. Washers 77 secure engagement between the slotted members 75 and bolts 76. Thus when it is desired to vary the distance between the block 35 and block 36, the bolts 76 are loosened, and spoke 70 is moved so as to bring the block 35 closer to the block 36. When the proper position has been reached, the bolts 76 are tightened, and the spoke 70 is rigidly fixed with respect to the drum 50. The actuating arms for the gripper 16 located in the drum 50 are positioned in the foreground of the side elevation of Figure 1. The actuating arms of the gripper 15 located in the spoke 70 are located in the rear of the side elevation shown in Figure 1.

The gripper arm 15 and its actuation are more clearly shown in Figure 2, where can be seen the gripper arm 15 which extends into, and is integral with, a shaft 80 gripped by a split member

81 which forms one end of an arm 82 carrying a roller 83 riding on the cam 84. The spring 85 fixed to the frame by the pin 86 presses the roller 83 down onto the cam 84. The cam 84 is mounted on bearing 87 which extends into the frame 90 where it is fixed. In Figure 2, the split member 62 which grips the pivot 18 is shown. The gripper 15 terminates at the point 89.

The corresponding gripper arms 15' and 16' and their actuated mechanisms are identified by the same numbers as gripper arms 15 and 16. It is to be understood that this double gripper cylinder has for speed of operation two sets of gripper arms as shown clearly in Figure 1, each set holding the creases in a single section of paper to form the bag bottom therein.

This double gripper mechanism of our invention provides a sure and accurate way of maintaining the gripped bag bottoms in proper position during the bottom forming operations. It is a radical improvement over the prior rubber groove which merely engaged, by frictional engagement, the creased bottoms. By means of the stationary cam and the arm actuated gripper which rotates with the drum, a synchronized gripping action is obtained. The adjustment of distances between the respective gripper arms is easily fixed as shown above. It has been found that the gripper mechanism herein provided makes possible elimination of inaccurate operation and slippage hitherto common in this art. It is a distinct step in removing, in bag making machines, the possibilities of malformation that have been so common.

Although we have set forth a specific mechanism for employing this positive gripping action, it is to be understood that we do not limit ourselves to the particular mechanisms which have been set forth by way of example, but we intend to cover broadly mechanisms that accomplish these results as set forth in the appended claim.

We claim:

A gripper cylinder comprising a drum, a groove in said drum, a gripper arm in said groove, said gripper arm being mounted to rotate on a shaft to move against a wall of the groove, said gripper arm being actuated by a second arm, said second arm carrying a roller, said roller being actuated by a cam, said gripper arm being impelled against the wall of said groove by means of a spring, said spring being mounted at the end of said second arm, an extension mounted on said second arm for moving said gripper arm away from said wall.
